UNITED STATES PATENT OFFICE.

JOHN W. SCOTT, OF WEST ALLIS, WISCONSIN.

WINDOW STRIP.

Application filed April 4, 1922. Serial No. 549,457.

To all whom it may concern:

Be it known that I, JOHN W. SCOTT, a citizen of the United States, and resident of West Allis, in the county of Milwaukee and State of Wisconsin, have invented certain new and useful Improvements in Window Strips; and I do hereby declare that the following is a full, clear, and exact description thereof.

10 My invention relates to window strips which are adapted to be inserted between the sash and the jamb.

15 Among the important objects of my invention are, the elimination of a large part of the expense incident to the use of weights and pulleys and the like, for supporting the sash at a point to which it may be adjusted, and the provision of resilient means for this purpose, which at the same time performs 20 the function of preventing the window from rattling and likewise serves as a weather strip.

25 The invention will be more fully explained in connection with the accompanying drawing, in which—

Figure 1 represents a sectional plan view thru a window frame with my invention applied thereto.

Figure 2 is a fragmentary perspective view showing the manner of applying the invention to the sash.

Figure 3 is a perspective view of the spring strip which is attached to the jamb, and

35 Figure 4 is a detailed view showing the manner of attaching the same.

Referring more in detail to the drawing, the numeral 5 indicates the jamb of the window frame, 6 the inside casing, 7 the blind stop, and 8 the window stop. The usual sashes 9 are mounted to slide up and down between the window stop and the blind stop.

40 My invention includes the provision of a jamb strip 10 which is formed from spring metal and which eliminates the use of weights and pulleys as well as the parting stop. This spring strip is formed with a pair of longitudinal beads 11, which extend in the direction of the sashes, and the por-

tions of the strip which extend outwardly 50 from the beads are inclined towards the jamb, as shown at 12, and terminate in flanges 13 which are folded so as to extend towards each other and are secured to the jamb. Each sash is provided preferably 55 with a metallic strip 14, which is formed with an inwardly extending groove 15 which is adapted to receive the corresponding bead 11. The flanges 13 are secured to the jamb by screws or brads 16, which may be 60 easily driven into the jamb thru holes 17 provided in the sloping surface 12.

The strip 10 is made of suitable width and shape, so that when it is secured to the jamb, the central portion thereof will be spaced 65 therefrom, and resiliently urged towards the sash, which is made of suitable size so as to closely engage the same. By means of this construction, the engagement of the two strips will be of sufficient strength to 70 support the sash in any position to which it is raised, and this close engagement, in connection with the curved form of the bead, will serve to effectually prevent the wind from coming thru the window, and will also 75 prevent the window from rattling.

Although for the purpose of illustration I have shown one specific way in which my invention may be carried out, it will be understood that various modifications may be 80 made in the structural details thereof without departing from the spirit of the invention.

I claim:

1. A device of the character described 85 comprising a pair of metallic strips adapted to be secured to a window jamb and the adjacent side of the sash respectively, one of said strips having a longitudinal groove formed therein and the other strip having a bead slidably engageable therewith, the latter strip being normally under spring tension so as to exert pressure in said groove to frictionally hold said sash in adjusted position. 90

2. As an article of manufacture, a metallic jamb strip for windows having a pair of longitudinal beads adapted to register 95

with corresponding grooves in the side edges of the sashes, the portions of said strip outside of the beads being inclined away from the beaded side and terminating in flanges which are turned toward each other underneath the inclined portions for contacting with said jamb, said inclined portions being provided with openings thru which screws

may be inserted thru the flanges to secure the strip to the window jamb. 10

In testimony that I claim the foregoing I have hereunto set my hand at Milwaukee in the county of Milwaukee and State of Wisconsin.

JOHN W. SCOTT.
